REFRIGERATOR FLASK

Walter R. Sterrett, Muncie, Ind., assignor to Ball Brothers Company, Incorporated, Muncie, Ind., a corporation of Indiana

Application December 7, 1954, Serial No. 33,430

Term of patent 14 years

(Cl. D58—25)

Fig. 1

Fig. 2

Fig. 3

Fig. 4

Figure 1 is a side elevational view of a refrigerator flask, showing my new design; the side of the flask that is opposite to the side of Figure 1 is the same as the side shown;

Figure 2 is an elevational view taken from the right of Figure 1;

Figure 3 is an elevational view taken from the left of Figure 1; and

Figure 4 is a top plan view thereof.

The design for the refrigerator flask disclosed is characterized by the vertically disposed ribs and the specific pattern resulting from the contrast occasioned by the stippled and unstippled surface of the flask.

I claim:

The ornamental design for a refrigerator flask, as shown and described.
